UNITED STATES PATENT OFFICE.

ROBERT W. BISSELL, OF NEW YORK, N. Y., ASSIGNOR TO VEGETABLE OIL SECURITIES COMPANY, OF PITTSBURGH, PENNSYLVANIA, A CORPORATION OF PENNSYLVANIA.

PROCESS OF AND APPARATUS FOR TREATING OILS.

Application filed April 15, 1920. Serial No. 374,006.

To all whom it may concern:

Be it known that I, ROBERT W. BISSELL, a citizen of the United States, residing at the borough of Manhattan, in the city, ⁵ county, and State of New York, have invented certain new and useful Improvements in Processes of and Apparatus for Treating Oils, of which the following is a specification, reference being had therein to ¹⁰ the accompanying drawings, which form a part thereof.

My invention relates to a process of treating oils by means of which the F. F. A. (free fatty acid) content of the oil may be ¹⁵ reduced and such acid and other volatile constituents may be removed from the oil, and the iodin number of the oil reduced without disrupting the oil cells, notwithstanding the elevated temperature at which ²⁰ the process is carried on; and to an apparatus so constructed and arranged as to be capable of use in the practice of such a process.

To successfully purify oils by the process ²⁵ of my invention, it is not only desirable to subject the oil, while being maintained at an elevated temperature, to the action of hydrogen or superheated steam, or both, but to bring such gases into intimate relation ³⁰ with the entire volume of the oil under treatment in a manner to ensure uniformity in the volume of gas mixed with a given volume of the oil, and of the interval during which the oil is subjected to the action ³⁵ of the gas, thus ensuring uniformity in the resultant product. With this end in view, I have evolved a process by which a considerable volume of oil may be treated by a continuous process, notwithstanding that ⁴⁰ at no time is any substantial volume of the oil subjected to the action of the refining gases and brought to a high temperature, and then for a comparatively short interval. By thus subjecting only a small volume of ⁴⁵ the oil to a high temperature and to the refining gases, and continuously renewing the supply of oil under treatment, from a main source of supply, I am enabled to bring the oil to the desired elevated temperature without subjecting it to the action of the heating medium for a material length of time, and I am also enabled to treat a ⁵⁰ relatively large volume of oil with a relatively small volume of gas by reason of the

possibility of securing an effective commingling of the oil and the gas, while securing the desired intimate contact of every part of the oil therewith. ⁵⁵

The gases introduced to the oil will bubble therethrough until they escape, carrying with them free fatty acid and other volatile constituents of the oil which are thereafter separated from the gases used for refining purposes, so that if desired these gases may thereafter be purified and ⁶⁰ again used. ⁶⁵

In order to affect the desired degree of purification of the oil, I may repeat the above treatment any desired number of times in succeeding stages, it being possible, in some of these stages, to use one gas, while in other stages, to use other gases, the oil having a slow circulation while being so treated, thus defining the duration of the interval of high temperature and gas contact during each stage. In fact a continuous process is secured through the maintenance of this slow circulation, which also results in uniformity in the treatment of the entire volume of oil and in the product. ⁷⁰ ⁷⁵

The process may be carried on under normal or under subatmospheric pressures, as desired.

In the practice of the process of my invention, I preferably employ an apparatus ⁸⁵ by means of which the oil to be refined may be continuously circulated, and every part thereof during this circulation, will be passed in a thick film between an oil feed pipe and an inner pipe connected with a source of supply of hydrogen, superheated steam, or both, so constructed as to discharge such gases into the flowing volume of oil with the twofold object of inducing a circulation of the oil about said gas pipe ⁹⁰ and ensuring the desired intimacy of the relation of said gases with the oil. Means are provided exteriorly of the oil feed pipe for bringing the oil to, and maintaining it at, the desired elevated temperature while ⁹⁵ being thus commingled with the gases. ¹⁰⁰

The apparatus employs a plurality of heating and mixing units, each being associated with a compartment, the lower portion of which serves as a storage chamber for the oil under treatment, and the upper part of which serves as a collecting chamber for the refining gases and the volatile ¹⁰⁵

matter passing from the oil therewith after their separation from the oil. Succeeding compartments are in communication with each other adjacent the normal level of the oil in the lower part of the compartment, so as to ensure the flow of the oil from one compartment to the other with the desired progression in the treatment of the oil, and limiting the oil thus passing from one unit 10 to the other, to that which has been subjected to the action of the gases, which oils will have lower specific gravity than those which have not been so subjected.

The oil circulation, the oil heating and the 15 gas distributing elements of each unit are so arranged that the oil will be withdrawn from adjacent the bottom of the compartment before being subjected to the refining gas, and will be delivered adjacent the top of the compartment after being so subjected to the gas.

Each compartment is provided with an 20 offtake system for the refining gases and the volatile matter removed from the oil therewith, which is so constructed as to condense the free fatty acid separated from the hydrogen or other gases.

In connection with the gas offtake system, I use a heat exchanger which will have the 30 twofold effect of assisting in the condensation of the free fatty acid and preheating the oil to be treated. I also construct the oil feed system and the oil offtake system in the form of a heat exchanger, so as to reduce the temperature of the refined oil being delivered, and utilize the heat units derived therefrom in preheating the oil before subjecting it to the gas treatment.

The invention consists in a process of 40 treating oils consisting in the novel steps and practices hereinafter specified and in an apparatus for carrying on said process, all as hereinafter set forth and described and more particularly pointed out in the claims 45 hereto appended.

Referring to the drawings,

Fig. 1 is a side view partly in elevation 50 and partly in section of an apparatus used in carrying on the process of my invention, said apparatus being broken away and condensed so as to disclose only a few of the units thereof;

Fig. 2 is a vertical section through the 55 supply tank, one of the gas offtake units and one of the heating and mixing units; and

Fig. 3 is a detail fragmentary view of a portion of one of the heating and mixing units.

Like letters refer to like parts throughout 60 the several views.

In the practice of the process of my invention, the oil in large volume may be stored in any desired manner so as to permit a continuing small volume thereof being withdrawn 65 and brought to an elevated temperature and

charged with a refining gas such as hydrogen, superheated steam, or a mixture of the two, while it is maintained at the desired high temperature. Ordinarily the oil will be brought to, and maintained at, a temperature of from 220° to 275° C. 70

In order to permit the rapid attainment of this high temperature, I preferably circulate a thick film of the oil in the space between two concentric tubes, the inner of 75 which has a plurality of holes through which refining gas is delivered to the flowing film of oil, thus ensuring the thorough admixture of the oil and gases with the use of a small volume of the latter. 80

The admixture of oil and gases is delivered to a compartment having relatively greater capacity than the tube from which the oil and gas is delivered, thus affording opportunity for the separation of the refining gases, and of those volatile constituents of the oil reduced to a gaseous form as a result of the elevation in the temperature of the oil and the reactions resulting from the intimate contact of the refining gases with the oil while at this elevated temperature. 85

The hydrogen or other refining gases will react upon the oil both while being maintained at the high temperature while flowing about the gas supply pipe, and during the process of separation from the body of the oil in the compartment into which the oil and gas admixture is delivered. 90

The refining gases and volatile constituents of the oil separated therefrom with the gases, are withdrawn from the upper part of this compartment sufficiently rapidly to prevent condensation of such constituents, particularly free fatty acid within the compartment, it being possible, and possibly desirable, to maintain a subatmospheric pressure in the upper part of the compartment, with the twofold object of facilitating a more rapid and complete separation of the refining gases and volatile matter from the oil, and evacuation of such matter after such separation. 100

The oil so treated, after the separation of the gases and other volatile matter therefrom, is withdrawn from said compartment and again subjected to the action of heat, to bring it to substantially the same temperature, and admixed with the same or other refining gases in the same manner as heretofore referred to, and discharged into a succeeding compartment to affect a separation of such gases and the volatilized impurities in the oil in like manner to that heretofore described. 115

This treatment may be repeated any desired number of times until the oil has attained the desired degree of purity. 120

The succeeding stages of the treatment afford a continuous process which will sub-

ject every particle of the oil to the same temperature conditions while in intimate relation with the refining gas, and will define and make uniform the duration of the 5 interval during which the oil is maintained at the elevated temperature, and is so subjected to the gases.

After the last stage of the treatment, the oil is withdrawn and cooled and is in condition 10 for commercial use, or for further treatment such as hydrogenation, if it is desired to harden same.

In the accompanying drawings, I have 15 illustrated an apparatus particularly adapted for use in carrying on the above described process. This apparatus comprises a storage tank *a* for the oil to be purified or refined, which tank may have any desired capacity, and into which oil is poured from time to 20 time. Associated with the tank *a* is a drum *b* provided with a plurality of transverse partitions *b'*—*b''*—*b'''*, etc., forming a plurality of compartments, the lower portions of which form chambers for the oil under- 25 going purification or refinement, and the upper portions of which form collecting chambers adapted to receive the refining gases and the volatile constituents separated from the oil therewith, to facilitate their removal from the apparatus.

The succeeding compartments are in communication with each other through openings *c'*—*c*, *c''*—*c''*, *c'''*—*c'''*, etc. in the partitions *b'*—*b''*—*b'''*, etc., said openings being 30 spaced above the bottom of said drum. The drum *b* may be of any desired length, and may be divided into any desired number of compartments, there being one compartment for each stage of the treatment of the oil 40 in the apparatus.

The drum *b* is provided with a charging header *d* and with a discharging header *d''*.

The tank *a* communicates with the header *d* through a pipe *e*, one end of which opens 45 adjacent but below the normal level of the oil in said tank *a*, and the other end of which discharges at a substantially central point of the header *d*, the said connecting pipe *e* having a heat exchanger arranged in the 50 length thereof so as to utilize the heat units in the finished product for preheating the oil prior to its delivery to said header *d*. A detailed description of this heat exchanger will be given when describing the oil off- 55 take system.

Each of the compartments in the drum *b* is provided with an oil circulating, an oil heating and a gas mixing unit by means of 60 which a closed continuous circulation of a portion of the oil in each compartment is maintained, the oil while so circulating being brought to the desired elevated temperature and having hydrogen or superheated steam, or both, intimately mixed therewith. Each of these units is a duplicate of

every other, so a detailed description of but one of them will be entered into.

Depending from each compartment in the drum *b* is a vertical pipe or tube *f* which is surrounded by a steam jacket *g*. Leading 70 from a point adjacent the normal level of the oil in, and opening into, each compartment above the adjacent open end of the pipe *f* is a second vertical pipe *f'* also surrounded by a steam jacket *g'*. The pipes *f* and *f'* are connected by the bottom fitting *f''*, thus forming a looped pipe connection, the inlet end of which opens adjacent the bottom of the drum *b*, and the discharge 75 end of which is adjacent but below the normal level of the oil in said drum, while the steam jackets *g* and *g'* are connected by the fitting *g''*. The steam inlet opening, which may be placed in communication with any desired source of superheated steam, is indicated at *g''*, while the steam outlet opening is indicated at *g'''*.

Extending vertically through and arranged concentrically with the pipe *f'*, and terminating above the upper end thereof in a deflecting cap *h'*, is a gas supply pipe *h* having a multitude of small openings through that portion thereof within the pipe *f'* so that the refining gas may pass therethrough into, and be thoroughly admixed with, the oil film between the pipes *h* and *f'*.

Leading from the upper part of each compartment in the drum *b* is a gas offtake pipe *i* of relatively greater capacity than the oil and gas feeding units associated with each compartment, which pipe extends downwardly and terminates in a collecting drum *j* adapted to receive and accumulate the condensate of free fatty acid and other condensates of volatile matter removed from the oil by means of the elevated temperature and the refining gas. This drum *j* is provided with a drain cock *j'* by means of which such condensates may be removed therefrom from time to time.

Passing through the downwardly extending reach of the offtake pipe *i* is one reach of a circulating pipe *k*, one leg of which opens into the tank *a* adjacent the bottom thereof, and the other leg of which opens into said tank at a point considerably above the bottom thereof, but below the point of the inlet of the oil feed pipe *e*. In this manner heat units from the gases flowing through the outlet pipe will be transferred to oil contained in the pipe *k*, and since one leg of this pipe communicates with the tank *a* at a higher level than the other leg which passes through the gas offtake pipe *i*, a convection circulation of oil will be set up in said pipe *k* which will preheat the oil contained in the tank *a*.

The drum *j* is provided with a gas offtake opening *j''* which may be connected with an exhauster, so that if decided either a slightly

elevated or subatmospheric pressure may be maintained in the various compartments of the drum *b*.

To equalize the pressures in the various compartments of the drum *b*, I provide, in each of the diaphragms or partitions *b'*, *b²*, *b³*, etc., openings such as *m*—*m'*—*m²* etc. adjacent the top of the diaphragms, and thus permit gases in the upper part of said compartments to freely flow from one compartment to the other.

Leading from the discharge header *d'* is an oil offtake pipe *n* which may be connected with any desired point of storage for the finished product. This offtake pipe has a coil in the length thereof which, in conjunction with the oil feed pipe *e* passing through the coils of this pipe, serves as a heat exchanger to transfer to the oil flowing from the tank *a* to the charging header *d* of the drum *b*, heat units in the finished oil product.

While I have herein referred to the use of superheated steam in the steam jackets of the oil heating units associated with the several compartments, and with the possibility of introducing such through the gas distributing pipe *h*, it is to be understood that this refers merely to a use of the apparatus when high temperatures are required, such as when refining vegetable or other fatty oils. If other material is to be treated, saturated steam may be used and if desired other means than a steam jacket may be used to bring the oil in the pipes *f* and *f'* and their connection *f²* to the desired high temperature.

While I have referred to the possibility of maintaining the desired level of oil in the tank *a* by pouring additional oil thereinto from time to time, I preferably provide means as the valve controlled pipe *o* leading from a storage tank of large capacity and discharging into said tank *a*, so that when the right conditions have been established, a continuous stream of oil may flow into said tank *a* in volume proportionate to that flowing from the drum *b* through the pipe *n* so as to ensure continuity in the operation of the apparatus without requiring constant attention.

The operation of the herein described apparatus is substantially as follows:—

In starting the apparatus, the tank *a* is first filled with oil, the oil, as said tank is being filled, filling the pipe *k* and flowing, when the proper level of the tank *a* has been reached, through the oil feed pipe *e* into the charging header *d*, and through the openings *c'*—*c'* in the partition *b'* into the compartment of the first stage of the drum *b*. While the oil is thus flowing from the tank *a*, steam is admitted to the steam jackets *g*, *g'* and *g²* entering through the steam inlet *g³* and passing through the steam out-

let *g⁴*, so as to ensure the highest temperature of the jackets being adjacent the gas mixing pipe *h*.

As soon as the oil has had opportunity to fill the circulation, heating and mixing unit associated with the compartment between the partitions *b'* and *b²*, the refining gas is delivered to the pipe *h* and passes through the various minute openings therein into the volume of oil between this pipe and the pipe *f'*. Since at this time the temperature of the oil will have been raised by the steam jacket, to that temperature at which it is desired to subject it to the action of said gases, and since the delivery of gas into the body of the oil will result in the formation of a multitude of small bubbles, the oil in the pipe *f'* will instantly rise and thus cause the oil in the compartment with which this unit is associated, to all gradually pass through this unit and be re-delivered to the compartment after being thoroughly admixed with gas while maintained at the desired temperature.

The charged and heated oil will be delivered adjacent, but below, the normal level of the oil in the compartment from which it is withdrawn, so that the oil already within said compartment which is of a very much lower temperature, will descend to the bottom of the compartment, and the charged oil will stay at the top of the body of oil in said compartment. As the charged and heated oil enters said compartment, the gas bubbles will burst, and the refining gases and other volatile matter will separate from the body of the oil and rise to the upper portion of the compartment, or the gas collecting chamber therein, and be withdrawn through the gas offtake pipe *i*, the heat therefrom being transferred to the oil contained in the pipe *k* with the twofold result of raising the temperature of the oil in the looped pipe *k* and condensing the free fatty acid content of the gases and other condensable matter therein which will be delivered in liquid form to the collecting drum *j*, the non-condensable gases being removed from said drum, and if desired, subsequently washed or otherwise purified and returned to the source of gas supply with which the pipe *h* communicates.

As the level in the compartment of the first stage of the drum *b* reaches the level of the openings *c²*—*c²* in the partition *b²*, the oil will flow from the first compartment to the adjoining compartment where it will again be circulated, heated and mixed with the refining gas, and thus pass through the apparatus, being successively and progressively subjected to these treatments until it finally reaches the discharge header *d'* and passes therefrom through the oil offtake pipe *n*.

By passing the oil through a sequence of

stages, impurities therein will be gradually removed without the necessity for a continuous subjection of the oil to the effects of heat and of the refining gases, and the 5 overheating of any portion of the oil is thus avoided. It is possible that in succeeding stages, even though the same temperatures and the same volume of gas be employed, there may be a variance in the rate of flow 10 of the oil in the circulating unit, owing to the variances in the specific gravity of the oil as the treatment thereof progresses. This condition will not in any way destroy the effectiveness of the treatment and might 15 have the effect of more thoroughly separating the deleterious constituents therefrom. If desired the capacity of succeeding units may be varied to meet changing conditions in the apparatus, although preferably I employ 20 interchangeable units.

If necessary, in starting the apparatus the feed of oil through the pipe *e* may be controlled until the working conditions are such as to ensure the entire volume of oil in the 25 various compartments of the drum *b* and their associated circulating and mixing units, having been brought to the desired temperature before a fresh and continuing supply of oil is delivered to the tank *a*. 30 When the right conditions, however, have once been established, the valve of the pipe *o* may be opened and thereafter the apparatus will operate continuously and automatically without any substantial variations as to 35 temperature conditions or the length of time to which the oil is subjected to the high temperatures, or the volume of refining gas admixed therewith.

By employing a plurality of succeeding 40 stages as described, and by heating only a small volume of oil, and mixing a refining gas therewith, I am enabled to reduce the interval during which the oil is subjected to the high temperatures necessary in carrying 45 on the process of my invention, and affect a more or less gradual and thorough separation of the deleterious ingredients from the oil. At the same time every particle of the oil passing through the apparatus and 50 delivered through the pipe *n* will have been brought into intimate and repeated contact with a refining gas, so that the entire volume of oil delivered will be of uniform quality.

By having the openings *c'*, etc. adjacent 55 but slightly below the normal level of the oil in each compartment, such oil flowing from one compartment to the other will be at the highest temperature, and will have been subjected to the action of the refining 60 gas.

In the event that any gas bubbles are carried from one compartment to another, these bubbles will remain at the top of the 65 volume of oil in the compartment into which it flows, so that it will not pass through the

heating and mixing unit of this compartment until the envelopes of the bubbles have burst and the gases escaped therefrom so that the oil descends by gravity toward the bottom of this compartment.

While the apparatus herein described is particularly adapted for use with hydrogen as the refining gas, it is apparent that different mixing units may be employed to deliver different refining gases in different 75 stages, or a combination of such gases in any stage.

It is therefore not my intention to limit the invention to the particular nature of the refining gas employed, nor to the particular 80 temperatures, particularly as such will vary with the nature of the different oils to be treated in accordance with my invention.

When hydrogen is used, all parts of the apparatus are preferably made of aluminum, particularly where the oils or volatile 85 matter contacts with the metal parts.

Having described the invention, what I claim as new and desire to have protected by Letters Patent, is:—

1. The herein described process of treating oils consisting in continuously withdrawing a small quantity of oil from a large volume thereof, flowing the oil thus withdrawn in a small stream through a confined 95 space, subjecting the flowing oil to an elevated temperature, and simultaneously charging it with a refining gas, delivering said flowing oil with said refining gas to and within the volume from which the oil is withdrawn, permitting the refining gas and the constituents of the oil volatilized as a 100 result of the action of the heat and of the refining gas upon the oil, to commingle with the oil in the volume from which it is withdrawn, and thereafter separate therefrom and withdrawing the refining gas and the volatile matter from adjacent the oil.

2. The herein described process of treating oils consisting in the removal of the deleterious volatile constituents of the oil by continuously withdrawing a small quantity of oil from a large volume thereof, flowing it in a succession of small streams through confined spaces, subjecting each 110 stream of flowing oil to an elevated temperature and simultaneously charging it with a refining gas, delivering said flowing oil with said refining gas to the volume from which it is withdrawn, permitting the 115 refining gas and the constituents of the oil volatilized as a result of the action of the heat and of the refining gas upon the oil, to separate from the oil after each application of heat and charge of gas thereto, and

120 withdrawing the refining gas and the volatile matter from adjacent the oil as it separates therefrom.

3. The herein described process of treating oils consisting in withdrawing a small 130

volume of oil from a body of oil being treated, flowing said small volume of oil in a small stream through a confined space, subjecting the flowing oil to an elevated 5 temperature and simultaneously charging it with a refining gas, delivering said flowing oil with said refining gas to the volume from which it is withdrawn, permitting the refining gas and the constituents of the oil volatilized as a result of the action of the heat 10 and of the refining gas upon the oil, to separate therefrom, delivering the mixture of oil and gas into the body from which it is withdrawn, continuously withdrawing oil from 15 adjacent the top of said body, and continuously delivering a fresh supply of oil to said volume.

4. The herein described process of treating oils consisting in the removal of the 20 deleterious volatile constituents of the oil by withdrawing small volumes of oil from a plurality of connected bodies of oil being treated, flowing said small volumes of oil in a succession of small streams through 25 confined spaces and subjecting each stream of flowing oil to an elevated temperature, and simultaneously charging it with a refining gas, delivering the mixture of oil and gas of each stream into the body from which it 30 is withdrawn, withdrawing the refining gas and the volatile matter from adjacent each body of oil as it separates therefrom, continuously delivering a fresh supply of oil to the first of said bodies of oil, and continuously withdrawing oil from adjacent 35 the top of the last body of oil.

5. The herein described process of treating oils consisting in the removal of the deleterious volatile constituents of the oil by 40 continuously withdrawing a small quantity of oil from a large volume thereof, flowing it in a succession of small streams through confined spaces, subjecting each stream of flowing oil to an elevated temperature and 45 simultaneously charging it with a refining gas, refining gases having different properties being charged into different streams of flowing oil, delivering said flowing oil with said refining gas to the volume from which it is withdrawn, permitting the refining gas 50 and the constituents of the oil volatilized as a result of the action of the heat and of the refining gas upon the oil, to separate from the oil after each application of heat and 55 charge of gas thereinto, and withdrawing the refining gas and the volatile matter from adjacent the oil as it separates therefrom.

6. The herein described process of treating oils consisting in continuously withdrawing 60 a small quantity of oil from a large volume thereof, flowing the oil thus withdrawn in a small stream through a confined space, bringing the flowing oil to a temperature of from 220° to 275° C., and 65 simultaneously charging it with hydrogen,

delivering said flowing oil with said refining gas to and within the volume from which the oil is withdrawn, permitting the hydrogen and the constituents of the oil volatilized as a result of the action of the heat 70 and of the refining gas upon the oil, to commingle with the oil in the volume from which it is withdrawn, and thereafter separate therefrom, and withdrawing the hydrogen and the volatile matter from adjacent 75 the oil.

7. The herein described process of treating oils consisting in the removal of the deleterious volatile constituents of the oil by 80 continuously withdrawing a small quantity of oil from a large volume thereof, flowing it in a succession of small streams through confined spaces, and bringing each stream of flowing oil to a temperature of from 220° to 275° C., and simultaneously charging it with 85 hydrogen, delivering said flowing oil with said refining gas to the volume from which it is withdrawn, permitting the hydrogen and the constituents of the oil volatilized as a result of the action of the heat and of the hydrogen upon the oil, to separate from the oil after each application of heat and charge of gas thereinto, and withdrawing the hydrogen and the volatile matter from 90 adjacent the oil as it separates therefrom.

8. An apparatus for treating oil embodying therein a container adapted to contain oil, two connected pipes, one of which leads from the bottom of said container, and the other of which discharges into said container adjacent the normal level of the oil therein, a refining gas supply pipe within said last named pipe, and communicating therewith, whereby gas is charged directly into the oil flowing through said last named pipe, a source of heat adjacent said last named pipe, means whereby unrefined oil may be delivered to said container, means whereby refined oil may be withdrawn therefrom, and an offtake system leading from the upper portion of said container, whereby the refining gases and the volatilized constituents of the oil may be withdrawn from said container after separation from the oil.

9. An apparatus for treating oils embodying therein a drum divided by a plurality of transverse partitions into compartments connected by means of openings in said partitions, each of said compartments being adapted to contain oil, and the opening therein being adjacent the normal level of the oil in the compartment, each of said compartments having associated therewith two connected pipes, one of which leads from the bottom of said drum, and the other of which discharges into said drum adjacent the normal level of the oil therein, a refining gas supply pipe within said last named pipe, and communicating therewith, whereby gas is charged directly into the oil

flowing through said last named pipe, a source of heat adjacent said last named pipe, an offtake system leading from the upper portion of said drum, whereby the refining gases and the volatilized constituents of the oil may be withdrawn from said drum after separation from the oil, means whereby unrefined oil may be delivered to one end compartment of said drum, and means whereby refined oil may be withdrawn from the other end compartment thereof.

10. An apparatus for treating oils embodying therein a drum divided by a plurality of transverse partitions into compartments connected by means of openings in said partitions, each of said compartments being adapted to contain oil, and the opening therein being adjacent the normal level of the oil in the compartment, each of said compartments having associated therewith two connected pipes, one of which leads from the bottom of said drum, and the other of which discharges into said drum adjacent the normal level of the oil therein, a refining gas supply pipe within said last named pipe, and communicating therewith, whereby gas is charged directly into the oil flowing through said last named pipe, a source of heat adjacent said last named pipe, and an offtake system leading from the upper portion of said drum, whereby the refining gases and the volatilized constituents of the oil may be withdrawn from said drum after separation from the oil, a storage tank for unrefined oil, a pipe leading therefrom and discharging into one end compartment of said drum, a pipe leading from a source of unrefined oil supply and discharging into said tank, whereby unrefined oil will be continuously supplied to said tank and to said drum, and means whereby refined oil may be withdrawn from the other end compartment thereof.

11. An apparatus for treating oils embodying therein a drum divided by a plurality of transverse partitions into compartments connected by means of openings in said partitions, each of said compartments being adapted to contain oil, and the opening therein being adjacent the normal level of the oil in the compartment, each of said compartments having associated therewith two connected pipes, one of which leads from the bottom of said drum, and the other of which discharges into said drum adjacent the normal level of the oil therein, a refining gas supply pipe within said last named pipe, and communicating therewith, whereby gas is charged directly into the oil flowing through said last named pipe, a source of heat adjacent said last named pipe, and an offtake system leading from the upper portion of said drum, whereby the refining gases and the volatilized constituents of the oil may be withdrawn from said drum after

separation from the oil, a storage tank for unrefined oil, a pipe leading therefrom and discharging into one end compartment of said drum, a pipe leading from a source of unrefined oil supply and discharging into said tank, whereby unrefined oil will be continuously supplied to said tank and to said drum, means whereby refined oil may be withdrawn from the other end compartment thereof, a looped pipe, one end of which leads from the bottom of said tank and the other end of which discharges into said tank above the bottom thereof, one reach of said pipe being subjected to the heated gases flowing through said offtake system, whereby the heat from said gas will be absorbed by the oil flowing through said pipe, and vapors flowing through said offtake system will be condensed, and a collecting drum adapted to receive such condensates.

12. An apparatus for treating oils embodying therein a drum divided by a plurality of transverse partitions into compartments connected by means of openings in said partitions, each of said compartments being adapted to contain oil, and the openings therein being adjacent the normal level of the oil in the compartment, each of said compartments having associated therewith two connected pipes, one of which leads from the bottom of said drum, and the other of which discharges into said drum adjacent the normal level of the oil therein, a refining gas supply pipe within said last named pipe, and communicating therewith, whereby gas is charged directly into the oil flowing through said last named pipe, a source of heat adjacent said last named pipe, and an offtake system leading from the upper portion of said drum, whereby the refining gases and the volatilized constituents of the oil may be withdrawn from said drum after separation from the oil, a storage tank for unrefined oil, a pipe leading therefrom and discharging into one end compartment of said drum, a pipe leading from a source of unrefined oil supply and discharging into said tank, whereby unrefined oil will be continuously supplied to said tank and to said drum, and an oil delivery pipe leading from the other end compartment of said drum having in the length thereof a coil through which said pipe discharging oil into said drum passes, whereby heat units from the oil withdrawn from said drum will be transferred to the oil flowing to said drum.

13. An apparatus for treating oils embodying therein a drum divided by a plurality of transverse partitions into compartments connected by means of openings in said partitions, each of said compartments being adapted to contain oil, and the opening therein being adjacent the normal level of the oil in the compartment, each of said compartments having associated therewith

- two connected pipes, one of which leads from the bottom of said drum, and the other of which discharges into said drum adjacent the normal level of the oil therein, a refining 5 gas supply pipe within said last named pipe, and communicating therewith, whereby gas is charged directly into the oil flowing through said last named pipe, a source of heat adjacent said last named pipe, and an 10 offtake system leading from the upper portion of said drum, whereby the refining gases and the volatilized constituents of the oil may be withdrawn from said drum after separation from the oil, a storage tank for 15 unrefined oil, a pipe leading therefrom and discharging into one end compartment of said drum, a pipe leading from a source of unrefined oil supply and discharging into said tank, whereby unrefined oil will be continu- 20 ously supplied to said tank and to said drum, and an oil delivery pipe leading from the other end compartment of said drum having in the length thereof a coil through which said pipe discharging oil into said drum passes, whereby heat units from the oil withdrawn from said drum will be transferred to the oil flowing to said drum, a looped pipe, one end of which leads from the bottom of 25 said tank and the other end of which dis- 30 charges into said tank above the bottom thereof, one reach of said pipe being subjected to the heated gases flowing through said offtake system, whereby the heat from said gas will be absorbed by the oil flowing 35 through said pipe, and vapors flowing through said offtake system will be condensed, and a collecting drum adapted to receive such condensates.
14. An apparatus for treating oils em- 40 bodying therein a container adapted to contain oil, two connected pipes, one of which leads from the bottom of said container, and the other of which discharges into said container adjacent the normal level of the oil 45 therein, a refining gas supply pipe within said last named pipe, and communicating therewith, whereby gas is charged directly into the oil flowing through said last named pipe, a steam jacket surrounding said last 50 named pipe means whereby unrefined oil may be delivered to said container, means whereby refined oil may be withdrawn therefrom, and an offtake system leading from the upper portion of said container, whereby the 55 refining gases and the volatilized constituents of the oil may be withdrawn from said container after separation from the oil.
15. An apparatus for treating oils em- 60 bodying therein a container adapted to contain oil, two connected pipes, one of which 65 leads from the bottom of said container, and the other of which discharges into said container adjacent the normal level of the oil therein, a refining gas supply pipe within said last named pipe, and communicating therewith, whereby gas is charged directly into the oil flowing through said last named pipe, connected steam jackets about both of 70 said pipes, the steam inlet of said jackets being adjacent said drum and said last named pipe, and the steam outlet opening being adjacent said drum and said first named pipe, means whereby unrefined oil may be delivered to said container, means whereby refined oil may be withdrawn therefrom, and an offtake system leading from the upper portion of said container, whereby the refining gases and the volatilized constituents of the oil may be withdrawn from said container after separation from the oil. 75
16. An apparatus for treating oils em- 80 bodying therein a drum divided by a plurality of transverse partitions into compartments, the lower portions of which are adapted to contain oil, and the upper portions of which are adapted to form chambers for the refining gas and volatile matter removed from the oil therewith, said partitions each having an opening therethrough below the normal level of the oil, and an opening there- 85 through above the normal level of the oil, whereby pressure conditions about all of said compartments will be equalized, each of said compartments having associated therewith two connected pipes, one of which leads from the bottom of said drum, and the other of which discharges into said drum adjacent the normal level of the oil therein, a refining gas supply pipe within said last named pipe, and communicating therewith, whereby gas is charged directly into the oil flowing through said last named pipe, a source of heat adjacent said last named pipe, and an offtake system leading from the upper portion of said drum, whereby the refining 90 gases and the volatilized constituents of the oil may be withdrawn from said drum after separation from the oil, means whereby unrefined oil may be delivered to one end compartment of said drum, and means whereby refined oil may be withdrawn from the other end compartment thereof. 95
- In witness whereof I have hereunto affixed my signature, in the presence of two sub- 100 scribing witnesses, this seventh day of April, 1920.
- ROBERT W. BISSELL.
